UNITED STATES PATENT OFFICE.

ALVIN S. STRICKLER AND WILLIAM H. STRICKLER, OF KEOKUK, IOWA.

CARPET-RACK.

SPECIFICATION forming part of Letters Patent No. 693,457, dated February 18, 1902.

Application filed September 13, 1899. Serial No. 730,322. (No model.)

To all whom it may concern:

Be it known that we, ALVIN S. STRICKLER and WILLIAM H. STRICKLER, citizens of the United States, residing at Keokuk, in the county of Lee and State of Iowa, have invented certain new and useful Improvements in Carpet-Racks; of which the following is a specification.

Our present invention pertains to improvements in carpet cabinets or racks, the construction of which is shown in the accompanying drawings, wherein—

Figure 1 is a perspective view of the rack or cabinet; Fig. 2, a perspective view of the 15 axle or spindle; Fig. 3, a similar view of one of the guard-supporting pins with a portion of a guard shown resting therein; and Fig. 4 a vertical sectional view taken through a roll of carpet, illustrating the relation of the spindle or support thereto.

The object of our invention is to provide a cabinet or rack wherein a number of rolls of carpet may be suspended in such a manner that the loose ends thereof may be drawn out 25 and brought to view and rewound upon the roll when so desired.

The body of the cabinet or rack comprises three or more upright members A, B, and C, connected at their top by a cross-bar D and 30 at their lower ends by a similar member E, a suitable base or footpiece F being provided for each upright.

In the form illustrated the spindle or support comprises two members or pins made tapering, as shown in Figs. 2 and 4. Each pin is formed with a series of wings or flanges G, which increase in height from the small end of the spindle to the outer or larger end thereof. Adjacent to the outer ends of the ribs or 40 flanges is formed a shield or guard H, from which extends centrally a stud-axle I, adapted when the parts are in position to rest and turn in suitable supports or bearing members J, secured upon the faces of the uprights, as indicated in Figs. 1 and 4. Said bearing members are provided with a rounded seat K and outwardly and upwardly inclined faces L, as best shown in Fig. 2. The pins forming the 45 spindle or support are driven or forced into the roll of carpet, the ribs or flanges causing the pin to form a tight connection therewith, and in case of Lowell or other carpets wound

upon a core having a square hole or socket serving to fit and fill the same. Before the pin upon the right-hand end of the roll is put 55 in place there is passed over the pin a spider-wheel M, formed with an opening adapted to fit around the ribs G. The faces of the outwardly-extending arms of the wheel which come next to the roll are formed in a plane 60 common with the body of the wheel, while the opposite sides of the arms extend out somewhat in order that they may be readily grasped by the attendant for the purpose of rewinding the roll or of assisting in unwinding it, as 65 the case may be. While we have spoken of putting the wheel on the right-hand pin, this is merely for the convenience of the operator, and it is obvious that it may be similarly placed upon the left-hand pin. 70

In order to form a support for the carpet as it is drawn from the roll and to better display it to the purchaser, and also to keep it from dragging on the roll below, we provide guard-bars N, said bars being supported by 75 suitable arms O, which are driven into holes or openings formed in the forward faces of the upright members A, B, and C, the arms being provided with enlargements P to prevent them from being driven in too far and 80 to bring their outer ends in alinement. The outer ends of the pins or arms are provided with seats or sockets Q, in which the ends of the rods or bars N are seated. Each bar is provided with two upstanding pins or eyes 85 R, which serve to guide the carpet and keep it straight as it is withdrawn from or rewound upon the roll. In practice we have employed simple screw-eyes for this purpose; but other forms of guide may obviously be employed. 90 These guides will or may be adjustable, the screw-eyes being so by reason of the readiness with which they may be screwed into the supporting-bar N at any point desired.

The guard-bar for each roll may be lifted 95 from its support at any time to facilitate the putting in and taking out of a roll. All of the parts are interchangeable, and the cabinet may be assembled and the rolls placed therein with but little labor. 100

No claim is made herein to the guard-bar and its supports as they are claimed in our application Serial No. 730,323, filed September 13, 1899.

Having thus described our invention, what we claim is—

In a cabinet or rack for displaying carpets and the like, the combination of a suitable framework or support; bearings carried thereby; a spindle adapted to hold a roll of carpet or the like, said spindle comprising two tapering pins provided with longitudinally-extending ribs or flanges, guards H at the outer ends of said pins, stud-axles I formed adjacent to each guard, and a power-wheel adapt-

ed to be mounted upon one section of the spindle.

In testimony whereof we have signed our names to this specification in the presence of 15 two subscribing witnesses.

ALVIN S. STRICKLER.
WILLIAM H. STRICKLER.
